GARMENT HANGER RAIL

August J. Baumgardt, Wauwatosa, Wis.

Application September 2, 1948, Serial No. 47,449

4 Claims. (Cl. 224—42.1)

1

The invention relates to garment hanger rail for automobiles.

The main object of the invention is to provide a garment supporting rail that may be readily mounted in the upper portion of the interior of an automobile where the roof of the car joins the upper portion of the sides, that may readily accommodate itself to cars of different widths and may be easily installed by a novice.

A further object of the invention is to provide a garment supporting rail comprising a pair of complementary bar members adjustably secured together and each provided with a side wall engaging foot, the over-all length of each member being somewhat greater than one-half the distance between the two points of anchorage of said rail, whereby, when said members are brought to an alined position, an upwardly arched rail is formed extending between the sides of the automobile.

The invention further consists in the several features hereinafter set forth and more particularly defined by claims at the conclusion hereof.

In the drawings:

Fig. 1 is a sectional view through an automobile showing my improved garment supporting rail installed therein;

Fig. 2 is a view similar to Fig. 1 showing the parts in vertical section;

Fig. 3 is a plan view of the structure shown in Fig. 1 in a partly assembled position;

Fig. 4 is a perspective view of wall engaging foot;

Fig. 5 is a detailed vertical sectional view taken on the line 5—5 of Fig. 2;

Fig. 6 is a detailed vertical sectional view taken on the line 6—6 of Fig. 2;

Fig. 7 is a detailed vertical sectional view taken on the line 7—7 of Fig. 2.

Referring to the drawings, the numeral 8 designates generally the body of an automobile which has the usual roof lining 9, the side wall lining 10, and a molding strip 11 that alines with the joining plane between the roof and the upper portion of the siding of the automobile.

The supporting rail comprises a pair of complementary rail members which are adjustably secured together and adapted when installed to engage the inner walls of the automobile under tension imposed on said rail members.

Each rail member includes a relatively long strip 12 of half the cross-sectional area of the full rail, a short strip 13 of half the cross-sectional area of the full rail, and a foot member 14. The strips 12 and 13 are of yieldable or bendable mate-

2

rial, preferably a suitable plastic composition or wood, and the foot members 14 are sheet metal stampings. As shown, each strip is of half round section to form a full circular section where the strips are superimposed though they may be of rectangular section to form a square or rectangle where the strips are superimposed.

Each foot member 14 has a grooved end portion 15 adapted to engage the molding strip 11 and an upwardly inclined hinge lug 16 which is secured to its rail member by a rivet or hinge pin 17 that passes through the outer ends of the superimposed long and short strips 12 and 13, said pin securing these strips together at this end of the rail while the other end of the short strip 13 is secured to the long strip 12 by a rivet 18.

Thin metal sleeves 19 having a bore 20 are provided to fit over the full cross-sectional area of the assembled strips.

20 The long strips 12 of each rail member being of similar cross section are adapted to overlap each other for a portion of their length and are provided with a plurality of spaced openings or holes 21, so that a bolt 22 passed through aligned holes in the strips 12 will secure them together at the intermediate portion of the completed rail. The positioning of this bolt 22 in the holes 21 is so chosen that the effective lengths of the strips 12 will be greater than the straight line distance between their points of anchorage at the sides of the automobile, so that the strips 12 will be initially in an angular position relative to each other when the feet 14 are engaging the molding, as shown in Fig. 3. Then the strips are pushed from their full line position in Fig. 3 to their alined dotted line position, and this has the effect of bringing the complementary strips together in an upwardly bowed position, aided by the inclined lugs 16, and in this position the sleeves 19 are slipped along each rail member until they engage the extended ends 23 of the adjacent rail member and thus hold the rail members in their assembled upwardly bowed position, the tension of the rail members through this bowing acting to securely hold the foot member 14 against the sides of the automobile, thus forming a strong rail on which garment hangers for coats or other wearing apparel may be hung. It will thus be noted that the actual clamping or holding pressure between the rails and the sides of the automobile is due to the tension imposed on the rail members themselves.

45 I desire it to be understood that this invention 50 is not to be limited to any particular form or

arrangement of parts except in so far as such limitations are included in the claims.

What I claim as my invention is:

1. In a garment hanger rail for automobiles, the combination of a pair of complementary yieldable rail members having foot members pivotally connected to their outer ends, means for lengthwise adjustably vertically pivotally connecting said rail members together intermediate their ends so that when said foot members are brought into contact with the interior sides of the automobile below the top thereof, said rail members will initially diverge from each other at their pivotal connections with said foot members and at their intermediate connection with each other, but when brought to an alined operative position, they will form an upwardly bowed rail secured to the sides of the automobile by the tension imposed by said alined rail members against said foot members, and means for securing said rail members in their alined bowed position.

2. In a garment hanger rail for automobiles, the combination of a pair of complementary yieldable rail members having foot members pivotally connected to their outer ends, means for lengthwise adjustably vertically pivotally connecting said rail members together intermediate their ends so that when said foot members are brought into contact with the interior sides of the automobile below the top thereof, said rail members will initially diverge from each other at their pivotal connection with said foot members and at their intermediate connection with each other, but when brought to an alined operative position, they will form an upwardly bowed rail secured to the sides of the automobile by the tension imposed by said alined rail members against said foot members, and means for securing said rail members in their alined bowed position.

3. In a garment hanger rail for automobiles, the combination of a pair of complementary yieldable rail members, each rail member having a pivoted foot member grooved to engage the molding strip of the automobile below the roof thereof and having an upwardly inclined pivot receiving lug, means for lengthwise adjustably vertically pivotally connecting said rail members together intermediate their ends so that when

said foot members are brought into contact with the interior sides of the automobile below the top thereof, said rail members will initially diverge from each other at their pivotal connection with said foot members and at their intermediate connection with each other, but when brought to an alined operative position, they will form an upwardly bowed rail secured to the sides of the automobile by the tension imposed by said alined rail members against said foot members, and means for securing said rail members in their alined bowed position.

4. In a garment hanger rail for automobiles, the combination of a pair of complementary yieldable rail members having foot members pivotally connected to their outer ends each rail having complementary half round portions secured together and a half round extension, means for lengthwise adjustably vertically pivotally connecting the half round extensions of said rail members together intermediate their ends so that when said foot members are brought into contact with the interior sides of the automobile below the top thereof, said rail members will initially diverge from each other at their pivotal connection with said foot members and at their intermediate connection with each other, but when brought to an alined operative position, they will form an upwardly bowed rail secured to the sides of the automobile by the tension imposed by said alined rail members against said foot members, and tubular sleeves slidably mounted on said rail members for securing them in their alined bowed position.

35 AUGUST J. BAUMGARDT.
